Application April 27, 1954, Serial No. 30,209

Term of patent 14 years

(Cl. D29—2)

To all whom it may concern:

Be it known that I, Clyde Le Roy Graham, a citizen of the United States, residing at New Castle, State of Delaware, have invented a new, original, and ornamental Design for a Badge, of which the following is a specification, reference being had to the accompanying drawing, forming a part hereof, wherein:

Figure 1 is a front elevational view of a badge showing my new design;
Figure 2 is a side elevational view thereof; and
Figure 3 is a top plan view thereof.
The dominant features of my design reside in those portions shown in full lines.

I claim:

The ornamental design for a badge, substantially as shown and described.
